UNITED STATES PATENT OFFICE.

CHARLES FUKUZO OAKA, OF LOVETTVILLE, ALBERTA, CANADA.

SAFETY SHOT-FIRER.

1,377,915.

Specification of Letters Patent. Patented May 10, 1921.

Application filed April 29, 1920. Serial No. 377,632.

To all whom it may concern:

Be it known that I, CHARLES FUKUZO OAKA, a subject of the King of Great Britain, a resident of the town of Lovettville, 5 Province of Alberta, Dominion of Canada, have invented certain new and useful Improvements in Safety Shot-Firers, of which the following is a specification.

This invention relates to improvements 10 in a portable safety shot firer, designed for use in mines and quarries, in conjunction with any suitable type of storage battery at present used (in mining operations), and the objects of the invention are to prevent 15 premature firing, to so control the firer that it is automatically locked in an inoperative position during the fixing of the connections of the electric circuit of which the firer forms a part, to permit of the firer being actuated only when the locking mechanism 20 has been released, so that the firer cannot be actuated unintentionally, because two operations are necessary one to unlock the firer, and the other to positively close the circuit 25 by manually operated means before a shot can be detonated.

Further objects are to facilitate mounting the firer on a belt so that it will be carried about by the wearer and always in position 30 to complete an electric circuit, to inclose the several working parts whereby they are not likely to be interfered with, but at the same time allowing of ready access for inspection and repair, and generally to 35 adapt the firer to better perform the functions required of it.

For a better understanding of my invention, reference is made to the accompanying drawings illustrating an embodiment of the 40 same and in which:

Figure 1 is a perspective view of the shot firer as seen when lying flat.

Fig. 2 is a rear elevation of the shot firer with the cover removed to show the mechanism housed within the casing.

Fig. 3 is a perspective view of the mechanism inclosed in the casing, and as seen when occupying a position similar to that shown in Fig. 1.

Fig. 4 is a transverse section on the line 4—4 of Fig. 2, the back cover however being in position.

Fig. 5 is a section on the line 5—5 of Fig. 4.

Like characters of reference refer to like parts in the several figures.

Referring to the drawings: A represents the improved shot firer comprising a casing 10 open at the rear and provided with a peripheral flange 11 to which the removable cover 12 may be secured by screws or the like.

The cover 10 is provided with channel-shape brackets 13 which engage the belt of the operator of the firer, and the firer is 65 portable, being carried about with the wearer.

On the front of the casing 10 a strip 14 of insulating material is provided on which a pair of V-shaped contact members 16 and 17 are provided, and these contact members are provided with posts 18 and 19, which extend into the interior of the casing.

The posts 18 and 19 are insulated from the casing 10 by suitable washers 20 and 21. 75

Rigidly secured to the bottom of the casing 10 is a block 22 of insulating material, which is of angle shape in longitudinal section, and is provided at one end with a pair of posts 23 and 24, which are spaced apart 80 and thus not in electrical contact with each other and on the upper end of the said posts switches 25 and 26 are pivoted.

On the opposite ends of the insulating block 22 to the posts 23 and 24 a pair of 85 contact members 27 and 28 are mounted, the said contact members being provided with posts 29 and 30.

The switches 25 and 26 are connected by a transversely extending member 31 of insulating material which is provided on the upper face with a bracket 32 provided with a pair of upwardly extending spaced jaws 33 having longitudinally extending slots 34 therein, and this bracket is spaced from the 95 switches 25 and 26 and thus does not make any electric contact therewith.

A cylinder 36 depends from the upper wall of the casing into the interior thereof, and a casing 37 is arranged longitudinally on the outer face of the upper wall of the casing 10. A plunger 38 passes through a portion of the casing 37 into the cylinder 36, and is provided at the lower end with a transversely extending pin 39 which engages with 105 the slot 34 in the jaws of the bracket 32.

The plunger 38 is embraced by the spiral spring 41, which is located in the cylinder 36, the lower end of the spring engaging the lower end of the cylinder, and the upper end of the spring engaging with a collar 42 which is fixed to the plunger 38. 110

That portion of the plunger 38 normally located within the casing 37 is provided with a peripheral V-shaped notch 43, and the upper end of the plunger 38 terminates in the thumb or finger grip 44.

A locking rod 45 is slidably mounted longitudinally within the casing 37, and is formed with an offset end 46 which extends through the slot 47 in the said casing, and 10 this locking rod is provided with a collar 48 between which and the end wall 49 of the said casing a spiral spring 50 is located.

This spring 50 encircles the locking rod 45, and the end of the locking rod is beveled 15 to engage with the V-shaped notch 43 in the plunger 38.

On the one end wall of the casing a conduit 60 is provided through which the wires 51 and 52 pass, and the wire 51 is attached 20 to the post 23, while the wire 52 is attached to the post 24.

The post 29 is connected by a wire 53 to one of the posts 18, and the post 30 is connected by a wire 54 with one of the posts 19.

25 The assembly of the firer will be readily understood from the foregoing description.

When the firer is to be used, the user passes his belt through the channel members 13 and thus secures the firer in a suitable 30 position, and thus the operator carries the firer about with him, and there is no possibility of the said firer becoming lost or misplaced, but will always be in the desired position ready for use.

35 When a shot is ready for firing, connections are made by the wires 51 and 52 with a cap which is to detonate the shot. The operator now takes the two wires leading from his battery and engages one wire with the 40 V-shaped contact 16 and engages the other wire with the V-shaped contact 17, an electric circuit is now completed and the closing is controlled by the switches 25 and 26.

45 When everything is ready for the shot to be fired, the operator retracts the locking rod 45 by engaging the thumb of his left hand with the offset end 46 and pulling the locking member longitudinally within the casing 37 thereby disengages the point of 50 the said locking rod from the V-shaped recess 43 in the plunger 38.

This movement releases the plunger 38 which may then be depressed by the operator applying pressure to the head 44 of the 55 plunger, so moving the plunger within the casing 10 until the switches 25 and 26 engage with the contacts 27 and 28.

In this way the gap between the posts 23

and 24 and the contacts 27 and 28 is bridged, and an electric circuit is completed whereby 60 a spark will be delivered to the cap attached to the shot to be fired so detonating the said shot.

As soon as the end pressure is released from the plunger 38, the said plunger will move upwardly to disengage the switches 25 and 26 from the contacts 27 and 28, so forming a break or gap in the electric circuit.

When the locking rod 45 has been released 70 it is moved longitudinally to reengage the point with the V-shaped recess 43 in the plunger 38.

From the above description, it will be seen that I have invented a shot firer which 75 is extremely simple in construction and is fool proof, because it prevents a shot being accidentally fired, and the firer is positively locked in position and requires to be intentionally operated before an electric circuit 80 can be closed by means of the same.

As many changes could be made in the above construction and many widely different embodiments of my invention within the scope of the claims, constructed without departing from the spirit or scope thereof, it is intended that all matter contained in the accompanying specification and drawings shall be interpreted as illustrative and not 85 in a limiting sense.

90 What I claim as my invention is:

1. A shot firer comprising a casing, a pair of posts in the casing, a pair of contacts spaced from the posts, arms pivotally mounted to the posts and designed to bridge 95 the gap between the posts and the contacts, an insulating member connecting the arms, a bracket on the insulating member, a plunger coacting with the bracket, the plunger being manually actuated in one direction, and resilient means for automatically actuating the plunger in the opposite direction. 100

2. A shot firer comprising stationary and movable contacts, an insulating bridge connecting said movable contacts and provided with a pair of spaced slotted jaws, and an actuating member for the movable contacts fitting between said jaws and provided with extensions engaging in the slots in the jaws. 105

110 In witness whereof I have hereunto set my hand in the presence of two witnesses.

CHARLES FUKUZO OAKA.
